Specification of Letters Patent. Patented Apr. 20, 1920.

Application filed April 14, 1919. Serial No. 290,301.

To all whom it may concern:

Be it known that I, AUGUST C. KLENKE, a citizen of the United States, and a resident of the city of Berkeley, county of Alameda, 5 State of California, have made a new and useful Invention—to wit, Clip; and I do hereby declare the following to be a full, clear, concise, and exact description of the same.

10 This invention relates to a paper clip which is of novel construction as far as I am aware.

The object of this device is to provide a paper clip which will be easy to place upon 15 the paper, and easy to remove when desired.

Another object is to provide a clip which will slip upon the paper and hold the various sheets in position without the danger of becoming separated through the accidental 20 removal of the clip.

Another object of this device is to provide a clip which will hold papers securely, and at the same time will allow the filing of the same without the danger of one paper being 25 slipped under a clip by error and consequently lost as far as proper filing is concerned.

In this specification and the annexed drawings, the invention is illustrated in the 30 form considered to be the best, but it is to be understood that the invention is not limited to such form, because it may be embodied in other forms, and it is also to be understood that in and by the claim following the description it is desired to cover the invention in whatever form it may be embodied.

In the drawings

Figure 1 discloses a perspective view of 40 my improved clip.

Fig. 2 is a side elevation of my improved clip.

Referring to the drawings more in detail, the numeral 5 designates a wire which 45 forms the body or clip when properly bent.

Starting at the point 6, the same is given a slight bend as at 7. At the point 8, I prefer to give my clip substantially a sixty degree bend, but at right angles to the plane 50 of the bend made at the point 7.

At the point 9, I again make a bend substantially semi-circular in shape and in the same plane as that of the bend indicated at 8, forming a V portion at this point 9.

At the points 10 and 11, I make bends of 55 sufficient contour to bring the part 12 substantially within the center of the side members 13 and 14, the part 13 passing beneath the part 15 before making the bend 10 and over the part 15 after making the bend 11. 60 I carry the part 12 to a point in close proximity to the V-bend 9, at which point 16 I bend the end 17 at right angles to the plane of the bend 11. This forms a clip having one end substantially locked over one side of 65 the clip, and having its free end upturned near the lower extremity of the clip.

In applying this clip, the first and second fingers are placed beneath the points 8 and 10, and the thumb brought to bear upon the 70 member 12 at substantially the point 18. Holding the clip in this position, it will be seen that by pressing slightly with the thumb upon the part 12 at the point 18, the upturned end 17 will be forced below the 75 plane of the side members 13 and 14. This will allow the papers to be held, being placed between the sides and the member 12, and the same can then be forced back to a point where they come in contact with the 80 cross member 15. When the papers are so placed, the upturned end 17 can be forced through the papers by a slight pressure upon the lower extremity of the member 12.

To remove the papers, it is only necessary 85 to reverse the operation, that is to press slightly on the papers at a point above 18 which will cause the point 17 to be disengaged from the small hole which it has punched in the paper; then by a slight pull 90 upon the portion between the points 10 and 11, the clip can be easily removed.

It will be seen by this structure that I have provided a clip which is cheap to manufacture, and at the same time combines 95 all of the advantages of the clips now upon the market, but with the increased advantage that my clip cannot be accidentally withdrawn from the paper nor is it possible for other papers to accidentally engage my 100 clip, which is really a great advantage.

It will also be noted that the loop formed between the points 10 and 11 forms a convenient means by which papers held within the clip may be hung upon a nail or file 105 without injuring the paper by punching large holes therethrough, it being understood that the hole made by the clip is very

small and therefore not to be considered. When hung upon a file, papers cannot drop out of my clip because of the portion 17 which passes through all of the papers.

5 Having thus described my invention what I claim as new and desire to secure by Letters Patent of the United States is as follows:—

10 In a paper clip formed of flexible resilient material of a substantially V-shaped portion, one end of said portion being bent so as to overlie the other side of said V in such a manner as to close said V and engage said other side, said other side of said V being

formed in a loop adapted to underlie said cross member at one point and overlie it at a point near the center of said cross member in such a manner that said cross member will serve as a fulcrum for said overlying portion, the free end of said overlying portion extending to a suitable point within said V and provided with an upturned end.

20 In testimony whereof, I have hereunto set my hand at San Francisco, California, this 31st day of March 1919.

AUGUST C. KLENKE.
In presence of—
A. J. HENRY.
